Inventor:
Lambert Diesel,
By Eugene Curran, *Attest*

UNITED STATES PATENT OFFICE.

LAMBERT DIESEL, OF CHICAGO, ILLINOIS.

ANTIGLARE DEVICE FOR HEADLIGHTS.

Application filed February 24, 1925. Serial No. 11,003.

This invention relates to anti-glare devices for automobile and other headlights.

The object of my invention is to provide a simple and inexpensive device which may be readily applied to a headlight glass or lens for diffusing the light and eliminating glare without appreciably lessening or dimming the amount of light emitted from the lamp.

10 The invention consists further in the matters hereinafter described and claimed.

In the accompanying drawings—

Fig. 1 is a front view of a headlight equipped with an anti-glare device of my 15 invention;

Fig. 2 is an enlarged vertical sectional view on line 2—2 of Fig. 1; and

Fig. 3 is a fragmentary view to illustrate 20 details of structure to be hereinafter described.

In Fig. 2 of the drawings, I have shown just enough of the headlight structure to illustrate the application of the invention thereto. In said figure, 1 indicates the outer 25 casing or shell of the lamp, 2 the parabolic reflector therein, and 3 the ring for clamping the headlight glass or lens 4 in place.

The device of my invention comprises two 30 relatively thin translucent discs 5, 6. These discs may be made of paper or other translucent material which will transmit light without appreciably dimming the same.

Said discs are provided with a plurality 35 of holes or apertures 7, 8 distributed over the same and arranged with the holes 7 in one disc staggered or offset from the holes 8 in the other disc, so that the holes in the respective discs will be covered by the imperforate portions of the other disc when the discs are placed one against the other, as 40 shown in Figs. 2 and 3. By this arrangement, there is only one layer of disc material covering the holes and two layers of disc material elsewhere. This allows more

45 light to pass through the discs at the holes than elsewhere and, as these holes are relatively small and are distributed over the entire area of the discs in a regular or uniform manner, the glare will be eliminated 50 without appreciably dimming or diminish-

ing the amount of light emitted from the lamp. This is an important advantage for automobiles, in that it allows night driving with the bright lights turned on to fully light up the roadway without the blinding 55 glare as heretofore.

The discs 5, 6 are usually applied against the glass or lens 4 on the inside and are clamped in place between the lens and outer edge of the opening covered thereby by the 60 ring 3, as shown in Fig. 2. The discs provide a simple and inexpensive device and one that may be easily and readily applied. In the drawings, the holes 7, 8 are laid out on a square formation with the holes at 65 certain corners of the squares.

I claim as my invention:

1. An anti-glare device for headlights, comprising two relatively thin, flat discs of translucent material, said discs being placed 70 one against the other and being substantially equal in size so as to be coextensive, one of said discs having a plurality of holes distributed over the same and covered by the imperforate portion of the other disc. 75

2. An anti-glare device for headlights, comprising two relatively thin, flat discs of translucent material, said discs being placed one against the other and being substantially equal in size so as to be coextensive, each 80 of said discs having a plurality of holes distributed over the same, said discs being arranged with the holes in one disc covered by the imperforate portions of the other disc. 85

3. An anti-glare device for headlights, comprising two discs of relatively thin, flat translucent paper material, each of said discs having a plurality of relatively small holes of substantially the same size distributed regularly over the same, said discs being arranged with the holes in one disc covered by the imperforate portions of the other disc so that there is a single layer of disc material at the holes and a double layer 90 of such material elsewhere. 95

In testimony that I claim the foregoing as my invention, I affix my signature this 20th day of February, 1925.

LAMBERT DIESEL.
